PROJECTILE

Madison H. Briscoe, 160 Valleywood Drive, Athens, Ga.
Filed Dec. 14, 1964, Ser. No. 418,036
9 Claims. (Cl. 102—38)

This invention relates to a new and improved projectile or bullet particularly suitable for hunting game.

One of the objects of the present invention is to provide a projectile which will inflict a highly effective wound on game and yet may be manufactured with various constructions that may be retailed at commercially competitive prices.

A more specific object of the present invention is to provide a projectile having a unique construction which upon striking a target such as game, will cause the projectile to ultimately turn and travel in a broadside position, that is, transverse with respect to the travelled path of the bullet whereby the size and shock of the inflicted wound will be substantially increased.

Other objects and advantages of the present invention will become apparent from the following description taken in conjunction with the attached drawings, in which:

FIG. 1 is a perspective view of a bullet representing a particular embodiment of the present invention;

FIG. 2 is a longitudinal cross-sectional view of the bullet shown in FIG. 1;

FIG. 3 is a diagrammatic view illustrating a sequence of movement of the bullet before and after it strikes a target;

FIG. 4 is a diagrammatic view of the bullet illustrating various forces which act on the bullet soon after it strikes a target;

FIG. 5 is a front end view of the bullet shown in FIG. 1 after it has entered the target and a nose portion thereof has been separated;

FIG. 6 is a side view of a bullet illustrating a second embodiment of the present invention;

FIG. 7 is a front end view of the bullet of FIG. 6;

FIG. 8 is a view similar to FIG. 7 illustrating a modification of the bullet of FIG. 6;

FIG. 9 is a side view of a bullet illustrating yet another modification of the bullet of FIG. 6;

FIG. 9b is a side view of a bullet illustrating still another modification of the bullet in FIG. 6;

FIG. 10 is a longitudinal cross-sectional view of another embodiment of the invention;

FIG. 11 is a longitudinal cross-sectional view of a modification of the embodiment of FIG. 10;

FIG. 12 is a longitudinal cross-sectional view of yet another modification of the embodiment of FIG. 10;

FIG. 13 is a longitudinal cross-sectional view of another embodiment of the invention;

FIG. 14 is a side view of another embodiment of the invention;

FIG. 15 is a side view of yet another embodiment of the invention; and

FIG. 16 is a side view of the bullet of FIG. 15 taken after the bullet has struck a target.

Referring to the drawings in detail, FIGS. 1 and 2 illustrate a particular form of the invention wherein a bullet generally designated 10 has a body 12 including an integral nose 14 formed from any suitable material such as lead or lead alloy. In the specific embodiment of FIGS. 1 and 2, nose 14 is generally conical and diverges into a cylindrical portion 16 of the body which is formed with a hollow or cavity 18. Powder 20 is provided in cavity 18 and sealing the latter is a cartridge case of suitable material including a cylindrical portion 22 surrounding and engaging body portion 16 and a base 24 disposed at the rear end of the body. A typical primer 26 is provided in base 24 of the case as shown in FIG. 2.

2

In accordance with the present invention, nose 14 is weakened by a score line or groove 30 formed in its periphery so as to define a plane which extends at an oblique angle to the longitudinal axis of the bullet as best shown in FIG. 1.

Groove 30 is made sufficiently deep so that when the bullet strikes the game or target, a nose portion 32 will be sheared or separated from the body along an oblique plane defined by groove 30 to thus present a corresponding oblique surface 34 (FIG. 5) at the leading edge of the bullet. Surface 34, because of its oblique disposition which results in an unsymmetrical or uneven distribution of the area on the leading end of the bullet, will produce unbalanced forces on the leading end of the bullet causing the bullet to turn in a broadside position with respect to the travelled path in the target such as designated by G in FIG. 3.

To briefly analyze the sequence of movement of the bullet after it is fired, reference is made to FIG. 3 wherein

position A illustrates the condition of the bullet as it is travelling to its target T while position B illustrates the bullet as it initially strikes target T. In positions A and B, the bullet is travelling in a rectilinear path and is also spinning about its longitudinal axis. Upon striking target

T, nose portion 32 is lost as described above, and referring for a moment to FIG. 4, there is diagrammatically illustrated in simplified fashion, forces which act on the bullet immediately after nose portion 32 has been severed. The driving force which impels the bullet forwardly is rep-

resented by D while the reaction force exerted on the bullet by the target is represented by R. The vertical component R_v of reaction force R produces an unbalanced force on the leading end of the bullet causing the bullet to shift into the position designated C which extends at

an oblique angle with respect to the original path of movement of the bullet. However, since the bullet is also spinning about its longitudinal axis, leading surface 34 is also rotating and consequently changing orientation so that, for example, when surface 34 has rotated 180° from position C, the vertical component R_v of the reaction force

will cause the bullet to shift into position E shown in FIG. 3. Thus, it will be apparent that the leading portion of the bullet will describe a circular path as the bullet travels through its target. At the same time, the rear end of the bullet will also describe a circular path, but of a lesser diameter than that described by the leading end of the bullet.

Once the vertical component R_v of the reaction force has displaced the leading nose of the bullet sufficiently from the rectilinear path, the bullet will abruptly turn to present its broadside to the target and will continue to drive through the target in this position until it exits or its driving force is dissipated.

Thus, up to several times the original square area of the nose can be brought to bear on the target.

In designing the size of the severable nose portion 32, it is important that it not be made large enough to cause a substantial loss in the bullet mass. It should be only a small fraction of the complete bullet mass, since it is important to retain all the mass and hence, momentum and broadside area possible with the main body of the bullet for maximum broadside effect. The examples shown are for many uses somewhat exaggerated for

clarity. Additionally, it will be appreciated that the size and angular orientation of the leading surface 34 together with the velocity, weight, construction, and overall shape of the bullet will determine how quick the bullet ultimately will turn in the broadside position. Accordingly, these factors may be varied to produce a desired effect.

Referring to FIGS. 6 and 7, another embodiment 40 of the invention is shown wherein the bullet is pre-formed, that is, manufactured, with an unbalanced nose 42 including a leading surface 44 extending generally obliquely to the longitudinal axis of the bullet but also being slightly convex as illustrated in FIG. 7. Alternatively, bullet 40 as well as bullet 10 described above, could also be constructed so as to present a concave leading surface which in FIG. 8 is illustrated as being made of two triangular sections 45. Likewise, the leading surface may be formed with a partially conical shape such as illustrated at 47 in FIG. 9.

Another embodiment is shown in FIG. 9b with a nose that has, or ultimately will take on, an unsymmetrical shape having a more or less flat area (y) and at a right angle to the longitudinal axis (x) as opposed to the rest of the nose area.

Since the unbalanced nose 42 of the bullet of FIG. 6 will cause it to gyrate while approaching the target, the accuracy of this bullet is somewhat lessened. However, for certain applications where extreme accuracy is not essential, the bullet of FIG. 6 will provide satisfactory results.

Turning to FIG. 10, there is shown another embodiment 50 of the invention wherein the severable nose portion 52 is formed separate from the bullet body 54. Nose portion 52 has an oblique rear surface 56 which seats against a matching surface 58 on the bullet body. Holding nose portion 52 against body surface 58 is a generally conical cap 60 which receives nose portion 52 in its closed end and extends onto a portion of the bullet body. A cylindrical jacket 62 is received on the remaining portion of the bullet body and suitably attached to cap 60 as at 64 to thereby hold cap 60 in place.

Sufficiently soft material is employed in forming cap 60 so that upon impact with the target, cap 60 will rupture and deform to release nose portion 52 and present surface 58 of the bullet body which will thus bring about the broadside effect as described above. Rupture of cap 60, may be facilitated by the provision of score lines or grooves (not shown) formed in the periphery of cap 60 in surrounding relationship to surfaces 56 or 58.

FIG. 11 illustrates a modification wherein the jacket, 66, is employed to hold the severable nose portion, 68, on the bullet body prior to striking the target. This is accomplished by lengthening jacket 66 so as to engage and hold the periphery of nose portion 68. In the bullet of FIG. 11, open end portion 69 of jacket 66 is formed of a reduced thickness so that upon impact with the target, jacket portion 69 will mushroom or deform to release nose portion 68 and thereby present oblique surface 70.

A further modification is shown in FIG. 12, wherein the jacket 74 is provided with an internal partition 76 extending obliquely between the opposite side walls of the jacket rearwardly or forward jacket portions 78. Nose portion 80 is held against partition 76 by jacket portions 78 which, upon striking the target, will deform to release nose portion 80 and present partition 76 as the leading, unsymmetrical, surface of the bullet. Additionally, in this embodiment, nose portion 80 is recessed at 81 and jacket portions 78 are received in recess 81 in flush relationship with the tip of nose portion 80.

In the modification of FIG. 13, nose portion 90 is comprised of two parts, namely, a wedge piece 92 seated against a correspondingly shaped oblique surface 93 formed on the bullet body 94; and a rivet or pin 96 which extends through wedge piece 92 into the bullet body 94 to hold wedge piece 92 in position. Pin 96 is formed from relatively soft material so that upon impact with the target, the stem 98 of pin 96 will shear to release wedge piece 92 and thus prevent the oblique surface 93 of the bullet body.

FIG. 14 illustrates another embodiment of the invention wherein a bullet 100 has a jacket 101 secured about

5 a soft core 102, which extends out of the jacket at the nose 103. On one side of the jacket 101 where the soft nose protrudes at 103 a cut, cuts or weakened area 104 is provided so that upon striking the target the soft nose will upset in an unsymmetrical, oblique surface because of the weakened side of the jacket.

FIG. 16 illustrates yet another form of the invention wherein a bullet 110 is weakened by a U shaped groove 112 which extends into the periphery of the bullet body along the sides of and around the nose thereof to define a plane generally parallel to the longitudinal axis of the bullet. Groove 112 is made sufficiently deep and terminates at 114 short of the rear end 116 of the bullet so that upon impact with a target, a portion 120 of the bullet will sever from the body along groove 112 and be deformed outwardly as shown in FIG. 16. The forces of resistance acting on deformed bullet portion 120 will thereafter cause the bullet to rotate clockwise (as viewed in FIG. 16) into the desired broadside position.

10 20 As will be apparent to persons skilled in the art, various modifications and adaptations of the structure above described will become readily apparent without departure from the spirit and scope of the invention which is defined in the appended claims.

25 What is claimed is:

1. A bullet comprising a body portion and a leading end portion generally at the forward end of the body portion, and means for separating said body portion and said leading end portion along complementary surfaces 30 upon impact with a target, the surface of separation of said body portion being such that an unbalanced surface area is presented on the forward end portion of said body portion causing the bullet to turn into a broadside position in the target after separation of the leading end 35 portion.

2. The bullet as defined in claim 1 wherein said body portion has a hollow core charged with powder and there is provided a cartridge case on the rear end of the body portion closing said core.

40 3. The bullet defined in claim 1 wherein said surface of separation of said body portion extends generally obliquely to the longitudinal axis of the bullet.

4. The bullet defined in claim 1 wherein part of said unbalanced surface area is rounded and part is flat and 45 generally at right angles to the longitudinal axis of the bullet.

5. The bullet defined in claim 1 wherein said leading portion is formed separately from said body portion and wherein said means includes a hollow jacket secured on said body portion and having a portion engaging the external surface of said leading portion.

6. The bullet defined in claim 1 wherein said surface of separation of said body portion is a partition inter-connecting sidewalls of the body.

55 7. The bullet defined in claim 1 wherein said means includes a cap having one end enclosing said leading portion and another end fixed to the body portion.

8. A bullet comprising a body having a nose on the leading end thereof, and frangible means for causing a portion of said leading end to separate from the body when the bullet strikes a target and thereafter causing an unsymmetrical surface to be presented on the leading end of the body thereby creating unbalanced resultant forces of resistance acting upon said unsymmetrical surface to cause the bullet to turn and travel broadside into the target, said frangible means including a portion formed integral with said body and nose, and said body having a groove formed in the periphery thereof generally defining the periphery of said unsymmetrical surface to be presented.

60 65 70 75 9. A bullet having a body and means on the leading end of said body for causing the bullet to travel into a broadside position in a target, said means including a groove in the leading peripheral surface of said body

dimensioned to cause a leading portion of said body to sever from the remaining portion of the body upon impact with the target.
